AUTOMATIC STOKER APPARATUS

Bert Daniel Wetmore, Bismarck, N. Dak., assignor to Henry M. Brooks, New York, N. Y., William Tudor Gardiner, Augusta, Maine, and Richard Kingsley Hawes, Fall River, Mass., trustees

Application June 20, 1927, Serial No. 199,877

6 Claims. (Cl. 110—101)

This invention relates to an apparatus for preventing the escape of smoke, gas or dust from an automatic stoker back into the fireroom.

Heretofore, in operating an automatic stoker, especially whenever the feed passage between the 5 hopper and furnace became empty for any reason smoke, gases and dust were likely to escape from the furnace back through the hopper into the fireroom.

It is accordingly the principal object of this 10 invention to provide an apparatus for preventing the escape of gases and dust into the fireroom through the feed passage of an automatic stoker or the like.

It is also an object of this invention to provide 15 an arrangement for preventing the escape of gases into the fireroom which may be conveniently incorporated in the apparatuses now in use for automatically feeding fuel to furnaces.

Other and further objects of this invention 20 will be apparent as the same becomes better understood from an examination of the specification and claims in connection with the accompanying drawing wherein.

Fig. 1 is a fragmentary longitudinal sectional view of a boiler provided with a stoker of the type to which this invention relates, and an arrangement embodying this invention.

Fig. 2 is an end view of the same.

Referring to the drawing more particularly, 30 numeral 3 represents the interior of the furnace in a boiler 4. The coal or other fuel is adapted to be fed to the furnace 3 by means of the stoker represented generally by the reference numeral 5.

The stoker 5 includes a feed passage 6 adapted 35 to discharge into a diverging mouth 7 beneath the bottom of the furnace compartment 3. The outer end of the passage 6 communicates with the bottom of a hopper 8 by means of which coal or other fuel is admitted to said passage. A feed 40 screw 9 is mounted longitudinally within the passage 6 and is driven through the intermediary of reduction gearing 10 by a motor 11. An air passage 12 surrounds the passage 6 and is adapted to deliver air to the furnace 3, and more particularly to deliver the combustion air to the fuel rising from 6.

The outer end of the passage 12 is connected to the discharge of a blower 13 also driven by the motor 11.

50 All of the parts just described are old and well known in the art. In the operation of these parts the coal or other fuel is supplied to the hopper 8 and thence is fed through the passage 6 to the furnace 3 by the revolving screw 9. It frequently happens in operating the automatic

stoker that the feed passage 6 becomes empty. In such a case smoke or other gases are likely to leak back through the passage 6 into the fireroom. It has been discovered also that sometimes air or other gases pass back through passage 6 even when the latter is not empty.

In order to overcome this difficulty I arrange 30 for the blower 3 to draw air across a surface, as it were, of the coal in the fuel supply system, and to this end preferably provide an angular hood 14 above the intake of the hopper 8 and connect 65 the top of this hood by means of a pipe connection 15 to the intake 16 of the blower 13. The vertical side 17 of the hood 14 is left open so that coal or other fuel may be admitted to the hopper. 70 By means of the hood 14 and the connection 15 therefrom to the intake of the blower 13 any smoke or other gases are returned through the air passage 12 to the furnace 3 together with all dust made in filling the hopper 8.

The pipe 18 which is connected, as shown in 75 Fig. 1, to the delivery side of the blower may be utilized for blowing a stream of air into the fuel feeding passage 6 at the inner end thereof toward the fire box to cause a positive flow of air in the passage toward the fire box. This arrangement provides further assurance against the leaking of gases outwardly through the passage toward the hopper.

It will be apparent that the aforescribed improvement may be conveniently and readily incorporated in automatic stokers or like apparatus now in use.

I am aware that many changes may be made throughout a wide range without departing from 90 the principle of this invention and I therefore do not wish to be limited to the details shown or described.

I claim:

1. The combination of a furnace having a fire 95 box and a stoker including a fuel passage leading to the fire box, a feed hopper on the outer end of said passage normally open to the atmosphere and to said passage, a blower and conduits connected thereto arranged for delivering air to said 100 furnace and arranged to induce a flow of air from the atmosphere across the inlet of the hopper.

2. The combination of a furnace having a fire box and a stoker including a fuel feed passage leading to the fire box, a feed hopper on the outer 105 end of said passage in open communication therewith and normally open to the atmosphere, means including a conduit connected with the hopper for causing a positive flow of air across the inlet of the hopper and into the fire box and con- 110

- structed and arranged to exert a slight suction through the hopper upon the outer end of said passage for conducting any outwardly flowing gases from the passage into the fire box and for preventing their escape into the atmosphere. 5
3. The combination of a furnace having a fire box and a stoker including a fuel passage leading to the fire box, an upwardly extending hopper on the outer end of said passage, a hood over said 10 hopper open to the atmosphere and providing communication from the atmosphere directly through the hood and hopper to said passage, a blower and conduits connected thereto and with the fire box and hood constructed to induce air flow 15 from the atmosphere through the hood across the top of said hopper and to deliver said air into the fire box.
4. The combination of a furnace having a fire box, a stoker including a fuel feed passage leading to the fire box, an upwardly extending hopper on the outer end of said passage open directly to the atmosphere, a hood over said hopper, a blower and conduits connected thereto and with the furnace and hood constructed to intake air through 25 said hood across the top of said hopper and de-
- liver the air into said furnace, and a pipe connected with the blower for directing air into said passage near the inner end thereof toward said fire box. 80
5. The combination of a furnace having a fire box, a coal stoker including a passage for coal leading to the firebox, a coal hopper at the outer end of said passage normally open adjacent its upper end and open to said passage to supply coal to the latter, a blower, and a conduit system for said blower, said conduit system including an inlet conduit leading to the inlet of said blower and a second conduit leading from said blower to said firebox to supply combustion air to the latter, and a hood at the inlet end of said inlet conduit, said hood extending over said open upper end of said hopper externally of said hopper and being open to admit air to said inlet conduit. 85
6. The subject matter of claim 5, characterized by the fact that said inlet conduit is so connected to said inlet of said blower that substantially all the air entering said blower passes through said inlet conduit. 90
